(57) **CLAIM**

The ornamental design for a coffee pod holder, as shown and described.

DESCRIPTION

FIG. 1 is a front, right and top perspective view of a coffee pod holder showing my new design;

FIG. 2 is a rear, left and bottom perspective view thereof;

FIG. 3 is a front elevational view thereof;

FIG. 4 is a rear elevational view thereof;

FIG. 5 is a right view thereof;

FIG. 6 is a left view thereof;

FIG. 7 is a top plan view thereof;

FIG. 8 is a bottom plan view thereof;

FIG. 9 is an enlarged view of a portion labeled as 9 on FIG. 1; and,

FIG. 10 is an enlarged view of a portion labeled as 10 on FIG. 2.

The long dash-short dash broken lines depict enlargement boundaries that form no part of the claim. The evenly broken lines illustrate portions of the article that form no part of the claimed design.

1 Claim, 10 Drawing Sheets
